(57) **CLAIM**

The ornamental design for an automotive instrument panel,
as shown and described.

DESCRIPTION

FIG. 1 is a perspective view of an automotive instrument panel;

FIG. 2 is a front view thereof;

FIG. 3 is a rear view thereof;

FIG. 4 is a left side view thereof, the right side view being
a mirror image;

FIG. 5 is a top view thereof;

FIG. 6 is a bottom view thereof;

FIG. 7 is another perspective view thereof; and,

FIG. 8 is a front view of the automotive instrument panel in
which an image, such as a navigational map, is displayed on
a display device, the image forming no part of the claimed
design.

The broken lines depict portions of the automotive instrument
panel in which the design is embodied that are not
considered part of the claimed design.

1 Claim, 6 Drawing Sheets
